CLAIM

What is claimed is an ornamental design for an isogrid structure, as shown and described herein.

DESCRIPTION

FIG. 1 is a perspective view of an isogrid structure; FIG. 2 is a side view of the isogrid structure shown in FIG. 1;

FIG. 3 is another side view of the isogrid structure shown in FIG. 1;

FIG. 4 is a bottom view of the isogrid structure shown in FIG. 1;

FIG. 5 is a top view of the isogrid structure shown in FIG. 1;

FIG. 6 is a side view of a portion of the isogrid structure shown in FIG. 1;

FIG. 7 is a side view of a portion of the isogrid structure shown in FIG. 1;

FIG. 8 is a perspective view of an isogrid structure shown in FIG. 1;

FIG. 9 is a side view of the isogrid structure shown in FIG. 8;

FIG. 10 is another side view of the isogrid structure shown in FIG. 8;

FIG. 11 is a bottom view of the isogrid structure shown in FIG. 8;

FIG. 12 is a top view of the isogrid structure shown in FIG. 8;

FIG. 13 is a side view of the isogrid structure shown in FIG. 8; and,

FIG. 14 is a top view of an isogrid structure.

The broken lines shown in FIGS. 1-14 illustrate portions of the isogrid structure that form no part of the claimed design.

1 Claim, 14 Drawing Sheets
